SINGLE BASE TRIPLE BEVERAGE MIXER

W. Arthur Ernst, Racine, Wis.

Application July 22, 1950, Serial No. 11,350

Term of patent 14 years

(Cl. D44—1)

To all whom it may concern:

Be it known that I, W. Arthur Ernst, a citizen of the United States, residing at Racine, in the county of Racine and State of Wisconsin, have invented a new, original, and ornamental Design for a Single Base Triple Beverage Mixer, of which the following is a specification, reference being had to the accompanying drawing, forming part thereof.

Fig. 1 is a view in perspective of a single base triple beverage mixer, showing my new design.

Fig. 2 is a plan view of the mixer base.

Fig. 3 is a view in front elevation of the mixer base.

Fig. 4 is a detail view taken in section on the line 4—4 of Fig. 2.

Fig. 5 is a detail view taken in section on the line 5—5 of Fig. 2.

Fig. 6 is a detail view taken in section on the line 6—6 of Fig. 2.

The dominant features of the design reside in the single base drawn in full lines as shown.

I claim:

The ornamental design for a single base triple beverage mixer, as shown and described.

W. ARTHUR ERNST.
